UNITED STATES PATENT OFFICE

HARVEY L. GLIDDEN, OF LEXINGTON, MASSACHUSETTS, ASSIGNOR TO UNITED SHOE MACHINERY CORPORATION, OF PATERSON, NEW JERSEY, A CORPORATION OF NEW JERSEY

BIN

Application filed January 8, 1928. Serial No. 80,128.

This invention relates to improvements in bins and particularly to bins for storing shoe lasts.

In the manufacture of shoes, it is customary to have on hand a large stock of lasts of various styles and sizes. Much of this stock is necessary in order that the manufacturer may be ready to meet the varying style requirements of the shoe trade, although a large proportion of the lasts may represent accumulations over a long period of time, due to changes in the style of the shoes. Because of the irregular shape and comparatively large bulk of lasts, and because it is desirable to keep separated lasts of different styles and of different sizes, it can readily be appreciated that the storage of lasts in such manner as to conserve valuable floor space is an important consideration. In one method of storing lasts, use has been made of bins provided with compartments for the reception of lasts of different shapes. One objection to such bins, as heretofore constructed, has been that they are not adapted for the reception of varying numbers of lasts of different styles and sizes without waste of storage space. For example, the factory run of shoes may be such as to necessitate the use of large numbers of lasts in certain styles and sizes so that the actual storage space required for the remainder of the stock of lasts in those styles and sizes is very much less than the maximum capacities of the bin compartments. Consequently, a great amount of space in the bins is wasted, some of the compartments being nearly empty, and a considerably larger number of bins is required than would be the case if each of the compartments were filled.

Furthermore, it has been found that the storage of last bins temporarily out of use is a serious problem in shoe factories owing to the comparatively large size of the bins. Also, it will be obvious that the cost to the shoe manufacturer of an integral bin structure of large size is increased by freight charges. Consequently, there has arisen in the trade a demand for last bins which can be knocked down and packed away in a small space when not in use.

In view of the foregoing, it is an object of this invention to provide an improved knock-down bin adapted for the reception of variable numbers of articles of different sizes, such as lasts, without waste of storage space. To this end, and as illustrated, there is provided a bin having bottom and side members hingedly connected together, end pieces for holding the bottom and side members in fixed position, and a slidably mounted transverse partition forming compartments the sizes of which can be varied in accordance with the number of articles placed therein, the construction and arrangement of parts being such that the bin can be so folded that it will occupy very little space.

In large shoe factories it is frequently found that a single bin is not large enough to store all the lasts of a given size. Accordingly, in another aspect the invention provides a bin construction in which two or more bin sections or units may be combined to form a single bin of large capacity. To this end, in the illustrated embodiment of the invention, each bin section or unit comprises bottom members, side members, a partition and detachable end pieces. In combining two sections an end piece is removed from each section, and corresponding members and partitions of the sections are secured together, the remaining end pieces being sufficient to maintain the members and partitions in rigid position.

Other features of the invention, together with certain details of construction and combination of parts, will be described in the specification and pointed out in the appended claims.

Referring now to the drawing,

Fig. 1 is a perspective view, partly in section of a last bin unit according to the invention.

Fig. 2 is a transverse cross-section through the last bin,

Fig. 3 is an end view of parts of a bin in folded position, and

Fig. 4 is a perspective view of portions of two last bin units showing the manner in which the units are attached to form an integral structure.

In its illustrated embodiment the invention consists in a bin open at the top and having outwardly flaring side walls. In transverse cross-section the bin is substantially hexagonal so that bins may be superimposed one upon another without rendering the interiors thereof inaccessible. The bin according to the invention is composed of one or more units, a single unit being illustrated in Fig. 1. Preferably and as shown, a bin unit is composed of two bottom members 10, side members 12, end pieces 14, and a longitudinally extending central partition 16. Each of these members comprises a skeleton construction of spaced boards attached to metal channels such as 18 by means of rivets as at 20. The bottom members 10 are attached to the central partition 16 by means of hinges 22, the side members 12 being similarly attached, respectively, to the bottom members 10 by hinges 24. The end members 14 are secured to the side and bottom members by means of bolts 26 and to a channel 28, forming part of the central partition 16, by bolts 30. This construction produces a rigid structure which is also light and strong.

Transverse partition members 32 are provided for dividing the bin into compartments. The partitions 32 are similar in construction to the end pieces 14 and are arranged to abut closely the central partition 16 on one side and a sloping side member 12 on the other side. Metal strips 34, located on the outside of the members 12, and bolts 36 serve to clamp the partitions 32 to the side members 12. Similarly, strips 38 and bolts 40 serve to clamp the transverse partition 32 to the central partition 16. The bolts 36 and 40 extend through spaces between the boards forming the members 12 and the partition 16, respectively, the heads of the bolts being received in recesses 42 provided in the members 32. It will be noted that the central partition 16 divides the bin longitudinally into two compartments, further subdivisions or compartments being formed by the transverse partitions 32. When it is desired to increase or diminish the size of a compartment to accommodate the compartment to a given number of lasts of one shape or size, bolts 36 and 40 of a partition are loosened and the partition is adjusted longitudinally of the bin and clamped in adjusted position by tightening the bolts.

To take down the bin for shipment or for storage, it is merely necessary to withdraw bolts 26, 30, 36 and 40, so that the end pieces 14 and transverse partitions 32 may be removed. The remaining members form a unitary structure which may be folded up as shown in Fig. 3. The side members 12 are swung inwardly, as indicated by the arrows in Fig. 3, until they contact with the bottom members 10 which are then swung on hinges 22 toward the partition 16. It will be noted

that each of the hinges 22 is bent into the shape of an L, the shorter arm 44 being slightly longer than the thickness of a member 12. This permits the side members to be positioned parallel and closely adjacent to the partition 16. In this manner, the parts of a bin when not in use may be made to occupy very little space without involving the necessity of completely disassembling the parts composing the bin.

The foregoing description relates to a bin construction comprising a single unit. However, where large numbers of lasts are to be stored, it is frequently desirable to provide bins of comparatively great length. Fig. 4 illustrates a portion of such a bin composed of two units, the construction of each unit being substantially the same as that which has been described in connection with Fig. 1. One of the end pieces is removed from each unit and the bolts 26 and 30, which in a single unit serve as attaching means for an end piece, are utilized to secure together corresponding bottom members 10, side members 12 and central partitions 16 of the two units which are placed in alinement and closely adjacent to each other. In this way a bin composed of as many units as desired may be constructed. It is to be noted that the construction of the partitions 32 is such as to make the bin structure more rigid than would otherwise be the case and renders it possible to combine several units without providing additional means for supporting the side members 12.

It is to be understood that while this invention has been illustrated and described in connection with bins for storing lasts, the invention is readily adapted for use in receiving and storing other articles.

Having described my invention, what I claim as new and desire to secure by Letters Patent of the United States is:—

1. A bin comprising a bottom member, a side member hinged to the bottom member, transverse partitions constructed and arranged to divide the bin into a plurality of compartments, said partitions being movable along the side member whereby the size of the compartments may be varied in accordance with the number and size of articles to be placed therein, and means for locking each of the partitions in substantially any position of adjustment along the side member.

2. A bin comprising a bottom member, a side member hinged to the bottom member, end pieces for holding the bottom and side members in fixed position, and a transverse partition slidably mounted for movement along the side member.

3. A last bin comprising bottom members, side members hingedly secured to the bottom members, end pieces, means for securing the end pieces to the bottom members, means for securing the side members to the end

pieces constructed and arranged to support the side members in fixed position, a longitudinal partition extending parallel to the side members, and a transverse partition extending between the longitudinal partition and one of the side members and movable along the longitudinal partition.

5 4. A bin comprising a bottom, side members, and a partition, all extending in the same general direction, connections between the side members and the bottom and between the bottom and the partition, the construction and arrangement of the members and connections being such that the bottom and each of the members may be folded into position parallel to said partition, and closely adjacent thereto, end pieces for engagement with the bottom, side members, and partition to hold them rigid when in unfolded position,

10 20 and a transverse partition extending between one of the side members and the first-mentioned partition.

25 5. A last bin comprising a partition, bottom members connected to the partition and swingable into planes parallel to the plane of the partition, and side members connected to the bottom members and swingable into planes parallel to said bottom members and said partition.

30 6. A bin consisting of a plurality of separable units, each unit comprising bottom and side members and a partition extending in parallel directions, means for detachably securing together the corresponding members and partitions of adjacent units, and means detachably connected to the ends of two of the units for maintaining the members and partitions in rigid position.

35 In testimony whereof I have signed my name to this specification.

40 HARVEY L. GLIDDEN.
